DETACHABLE CRANK AND COUNTERBALANCE FOR OIL WELL PUMPING MACHINES

Robert Boyd Dunlap, Shreveport, La.

Application November 5, 1932, Serial No. 641,340

6 Claims. (Cl. 74—591)

The invention relates to an improvement in combination cranks and counterbalances for attachment to the crank shaft of well pumping units.

5 One of the objects of the invention is to provide a counterbalance and crank arm which may be quickly and readily attached or detached from the crank shaft, so that the shaft will be free to rotate in performing the servicing operations 10 upon the well.

Another object of the invention is to provide a crank arm which includes a counterbalance which may be quickly attached or detached from the crank shaft by clamping the crank arm to the 15 shaft with a releasable crank.

Another object of the invention is to provide a crank arm which is adapted to be clamped to the crank shaft by a pivoted lever construction which may be firmly bolted in position to compel the 20 crank arm to rotate with the crank shaft as a unit.

Another object of the invention is to provide a crank arm having a lever construction which permits a mechanical advantage in clamping the 25 crank arm to the crank shaft.

Other and further objects of the invention will be readily apparent when the following description is considered in connection with the accompanying drawing wherein:

30 Fig. 1 is a side elevation of the invention applied to a crank shaft and clamped in its operating position.

Fig. 2 is an edge view showing the construction of Fig. 1.

35 Fig. 3 is a sectional view taken on the line 3—3 of Fig. 1 and looking in the direction of the arrows.

Fig. 4 is a diagrammatic view of the invention applied to an oil well pumping mechanism.

40 The invention will be best understood by having reference to Fig. 1 wherein the pumping mechanism is indicated generally at 2 and includes a walking beam 3, which is connected to the pump rods 4, which in turn extend through the well head 5 to the pump, which is located near the bottom of the well. Reciprocation of the string of rods 4 causes operation of the pump to lift the fluid from the well. The rods 4 are reciprocated by the oscillation or rocking movement of the 45 walking beam 3. The pitman 6 is connected to the walking beam to cause rocking movement thereof and the pitman is in turn caused to move by being connected to the crank arm 7, which is mounted for rotation with the crank shaft 8.

50 55 The crank shaft 8 it is to be understood is rotated

by any suitable source of power and may have mounted thereon a bandwheel such as 9, or it may project from any of the standard forms of reduction gears generally designated in the field as a pumping unit. The crank shaft 8 is mounted upon the usual jack post 10, which serves as a bearing to support it for rotation.

5 The invention particularly relates to the construction of the crank arm 7 and the associated parts whereby the crank arm may be attached or detached from the crank shaft 8. Fig. 1 shows the crank arm 7 as including the frame 15, which is provided with an edge rib 16 and web 17, which is cut away, as at 18, to lessen the weight adjacent the center of rotation.

10 The frame 15 is, however, provided with the shaft receiving opening 20 near its center. This opening 20 may or may not be provided with a plurality of transverse slots or grooves 21, which are adapted to receive the keys or clutch faces 22. 15 These keys may be moved into the grooves laterally and are adapted to project slightly above the face 23 of the opening so that they will abut against the bushing 24, which is keyed to the crank shaft 8, at 26'. Three of these keys 22 have 20 been shown but it is understood that any desired number may be provided.

25 In order to clamp the frame to the crank shaft 8 and the bushing 24 a lever or clamp 25 has been 30 provided. This lever is preferably quite massive and is arranged to receive the pivot pin 26, which is carried by the spaced flanges 27 on the frame 15. This is in the form of a tongue and groove construction wherein the tongue 28 is formed as part of the lever 25, while the groove is that space 35 between the two flanges 27 on the frame. Thus, the lever or arm 25 is arranged to pivot with respect to the frame 15. The arm 25 carries a key 30, which is similar to that of the keys 22, as seen 40 in Fig. 1. The keys 22 and 30 are spaced on thirds of the periphery of the bushing 24. When it is desired to attach the combination crank arm and counterweight to the crank shaft the arm 25 is 45 pivoted about the pin 26 in an anticlockwise direction as viewed in Fig. 1, until the arm is carried around to the position illustrated.

50 The end of the arm is provided with a slot 35, which receives the bolt or latching device 36. A nut 37 threaded on with the bolt 36 may be turned down to move the lever arm toward the frame. 55 This movement causes the key 30 to force the bushing 24 against the keys 22 carried by the frame until the crank arm and counterweight are securely latched or clamped to the bushing and crank shaft. The bolt 36 is pivotally mounted in 55

the frame as at 38, so that it may readily receive the crank arm and clamp it to the frame. When it is desired to remove the crank arm so that the well may be serviced, it is only necessary to release the nut 37 so that the arm 25 may release its clamping action upon the bushing 24.

The frame 15 serves as the crank as well as the support for the counterbalance and is provided with a plurality of openings 40, which are arranged to receive the wrist pin 41 by which the pitman 6 is connected to the crank arm in a manner well known in the art. A plurality of the openings 40 are provided in order to obtain different length strokes for the pumping mechanism.

The frame 15 has an enlarged outer end 45, which is shown in Fig. 2 as being somewhat thickened in order to provide a massive weight which will serve to counterbalance the string of rods 4 and the column of fluid in the well. Because of the walking beam 3 the crank arm is traveling downwardly when the rods and column of fluid are moving upwardly. Therefore, if a counterweight is provided it should be moving downwardly to help raise the fluid and to move upwardly to resist the falling of the fluid on the reverse stroke.

The amount of counterweight necessary on any particular well is dependent upon a number of variable conditions, such as the depth of the well, the specific gravity of the fluid, the friction of the pump, and the straightness of the hole. The body 45 will, therefore, be provided with openings or connections for any desired number of additional weights which may be attached or detached to the frame in order to obtain the proper amount of counterbalance. In some instances it is desirable to have the center of gravity of the counterweight ahead or behind the center line of the wrist pin so that the weight will either be applied ahead or behind the ends of the pumping stroke. With this in mind, the weights may be attached to either the right or the lefthand side of the frame as viewed in Fig. 1.

The attaching of weights to the frame in this manner is old and well known in the art and does not constitute any part of the present invention and for this reason the same have not been shown in the drawing.

While the keys 22 and 30 have been shown as circular members which fit into the grooves 21, which are slightly more than a half circle so that the pins will not drop out of position when the crank arm is disconnected, it is to be understood that they may be in the form of keys or shoes of any desired shape or configuration, the principal feature being to obtain a clamping action on the bushing 24 so that the crank arm and crank shaft will be compelled to rotate as a unit.

It is contemplated that a suitable support may be positioned below the crank shaft to receive the frame, crank arm and counterweight construction when it is released from its position on the crank arm. The lever 25 is of advantage in manipulating this massive construction because when the nut 37 is released the arm 25 will move upwardly as viewed in Fig. 1, so that the frame and counterweights will be gradually lowered away from the crank shaft. The inside face 50 of the clamping arm 25 will thus cam over the top curved surface of the bushing and, by controlling the movement of this lever 25 as it is being released, serves to control the lowering movement of the counterweight and crank arm, because of the great mechanical advantage obtained from

this lever construction it is possible for a single man to attach or detach the counterbalance construction. The present combination crank and counterbalance may be clamped to the crank shaft in any radial position.

When it is desired to attach the construction the weight is merely positioned beneath the crank shaft and the lever 25 carried around the crank shaft in an anticlockwise direction as viewed in Fig. 1. By pressing upon this lever the entire counterbalance construction is drawn upwardly around the shaft until such time as the nut 37 can be started onto the bolt 36. While the bolt 36 has been shown as merely projecting through the nut 37 a short distance, it is to be understood that this bolt may be of any desired length so that the nut 37 may be used to draw the lever arm around the crank shaft. It will be noted that the frame 15 is cut away around the bolt 36 and the pin 38 so that this pin may pivot to be passed through the opening 35 in the end of the lever arm. The opening 35 is of greater area on the inside of the arm than it is on the outside surface so that the bolt 36 may be readily passed therethrough.

The invention contemplates broadly the quick clamping and releasing of the crank arm to a crank shaft and which crank arm may or may not be provided with a counterweight assembly.

What is claimed as new is:

1. A crank arm for well pumping including a frame, a clamping lever connected thereto and extending along one side thereof, an opening formed by a part of said arm and said lever to receive the crank shaft, and means to lock said lever to the side of said frame to clamp said frame to the crankshaft for rotation.

2. A crank arm comprising a wrist pin receiving portion, a frame extending therefrom which is enlarged to form a counter weight, and means to clamp said frame to the crankshaft including a lever to draw the crank arm against the crankshaft.

3. A combination crank arm and counterbalance weight for well pumping including a frame of substantially triangular configuration, a lever pivoted to the apex of said frame, a recess in one of the sides of said frame to receive the crankshaft, said lever being adapted to overlie said recess, and means to draw said lever against the side of the frame to clamp the crankshaft in said recess.

4. A counterbalance frame adapted for attachment to a crank shaft, a socket to receive the crank shaft, a clamping lever pivoted to said frame adjacent said socket and shaped to cooperate with said frame to encircle the crankshaft, said lever being of a length to extend along said frame and be clamped thereto.

5. A counterbalance frame adapted for attachment to a crank shaft, a socket to receive the crank shaft, a clamping lever pivoted to said frame adjacent said socket and shaped to cooperate with said frame to encircle the crankshaft, said lever being of a length to extend along said frame and serve as a hoist to elevate said frame to position said crank shaft in said socket.

6. A crank arm counterbalance frame including a crankarm portion, a counterbalance portion, and an attaching portion, said attaching portion including a recess to receive the crankshaft and a lever to be passed over the crankshaft and to draw said frame into contact with the crank shaft.
